CLAIM

The ornamental design for an electric grinder as shown and described.

DESCRIPTION

FIG. 1 is a front, right side, perspective view of an electric grinder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded perspective view thereof;

FIG. 9 is a front view thereof, showing an activated power button; and,

FIG. 10 is a front perspective view of the electric grinder, shown in a state of use with environmental subject matter. The broken lines indicate portions of the article that form no part of the claimed design: the broken lines showing of the power button in FIG. 9 and the stand base and other electric grinders in FIG. 10 illustrate environmental structure and form no part of the claimed design.
